UNITED STATES PATENT OFFICE.

CHARLES ASHTON HENRY BULLOCK, OF LONDON, ENGLAND.

MACHINE FOR DELIVERING AND AFFIXING POSTAGE-STAMPS AND THE LIKE.

1,147,208.

Specification of Letters Patent. Patented July 20, 1915.

Application filed November 13, 1911. Serial No. 660,014.

To all whom it may concern:

Be it known that I, CHARLES ASHTON HENRY BULLOCK, of London, in the county of London, England, have invented certain new and useful Improvements in Machines for Delivering and Affixing Postage-Stamps and the like, of which the following is a specification.

This invention relates to an improved machine for delivering and affixing postage stamps and the like and has reference to machines of the kind wherein the operation of a plunger serves to feed a stamp forward, sever it and apply it to a surface.

The object of the present invention is to provide a more simple and reliable machine than those hitherto proposed and the invention comprises various important features of novelty which will hereafter be more particularly described and set forth in the claims.

Among these primary features of the invention may be specifically mentioned the feeding device wherein when the plunger is depressed the stamp strip is automatically gripped and fed forward the required distance, a pin or tooth preferably adapted to always spring back to a definite point automatically operating in conjunction with the perforations in the stamp strip to regulate and correct the feed. Secondly the damping device is important, the essential feature of which damping device is that jets or sprays of moisture are intermittently ejected from the machine in such a manner and in such a direction that the moisture is sprayed onto the adhesive side of the stamp to be affixed as the stamp moves into position for affixing.

Another feature consists of the particular arrangement of the plunger pad which presses the damped stamp on to the surface to which it is to be applied, the arrangement being such that instead of a vertical pressure only being available there is a slight horizontal movement of the pad such as will cause a more firm adherence.

Another feature consists of the means for preventing pilfering from the machine and this consists of a device which, if any attempt is made to withdraw a stamp without operating the plunger, pierces and damages the stamp and makes it necessary for the

machine to be opened to set it in working order again.

55

The invention moreover comprises the construction, arrangement and combination of parts hereinafter set forth.

In order that the invention may be readily understood and carried into practice, reference is hereby made to the accompanying drawings which illustrate a complete machine constructed in accordance with my invention.

In these drawings Figure 1 is a sectional 65 elevational view of the machine. Fig. 2 is a sectional plan view, the section being taken on line A—A of Fig. 1. Fig. 3 illustrates to a larger scale the arrangement of the plunger pad and severing knife. Figs. 4 and 70 5 are perspective views of details also drawn to a larger scale than Figs. 1 and 2, while Fig. 6 shows a modification of an important movement.

Referring to these drawings wherein like 75 numerals of reference indicate corresponding parts wherever occurring the numeral 1 designates the machine plunger which slides in an opening 2 in the casing 3 and is adapted to normally adopt its highest 80 position under the influence of a spring such, for instance, as the spring 4. Rigidly secured in a suitable manner to the plunger 1 a feed grip 5 is provided. This grip 5 is spring controlled preferably by the resilience of the arm 6 so that its rubber or yielding face 7 always tends to press upon the surface with which it contacts.

The numeral 8 designates the guide down which the stamp strip 9 passes from the roll 90 10 which is carried upon the spindle 11 and is housed within the circular extension of the machine casing. Normally the face 7 of the feeding grip 5 is held away from the stamp strip by reason of the pins 12 resting on the side blocks 13. When however the plunger 1 is depressed the pins 12 leave the block 13 and the face 7 falls on to the stamp strip and grips it in conjunction with the guide 8 or a sliding carriage 14. That 100

is to say, the strip is firmly gripped between the face 7 of the gripping device 5 and the guide 8 or a gripping piece such as 15 on the carriage 14. As the stamp strip is gripped the pins or the like 16 upon the 105 ends of the spring arms 17 which normally

engage in the perforations of the stamp strip are lifted out of these perforations by reason of the pins 12 engaging the blocks 17^a on the arms 17. Immediately the pins 5 12 leave the blocks 17^a—that is when the stamp strip has been moved forward a short distance—the pins 16 contact with the stamp strip in readiness to spring into the next row of perforations, and the stamp strip 10 is free to move and as the plunger 1 continues its descent the strip is moved forward and a stamp is ejected through the slot 19 in the member 20. When however a complete stamp has been extended through 15 this slot 19 the pin 16 will enter the next set of perforations in the stamp strip and prevent further movement and the knife 21 carried upon the bottom of the plunger will sever the stamp. The spring 17 is preferably anchored by a spring such as 16^a so 20 that the stamp strip can be fed a little too far at each operation, the carriage 14 moving back to insure correct feeding under all conditions.

25 When the feeding grip 5 has traveled downward sufficiently to extrude one or a length equal to a little more than one stamp through the mouth of the slot 19, the pins 12 make contact with stationary inclines 60. 30 The feeding grip 5 continues to travel downward but is lifted from the surface of the stamp in consequence of the action of the pins 12 which are forced to the right of their previous vertical course by said inclines 60 35 along which they travel until they have passed the spring points 61. The spring points 61 consist of leaf springs riveted or otherwise secured to stationary rails 62 which may be connected to the side of the 40 machine. The leaf springs are shown extending along the whole length of the rails 62 of which they form the tread although they need not do so. The pins 12 in passing the points 61 lift them. The points immediately spring back against the inclines 60. 45 On the return movement the pins 12 are compelled to pass along the right hand side of the rails 62 by the spring points 61, the resilient arm 6 yielding to permit them so to do. The feeding grip 5 is held free of the 50 stamp strip by said rails 62 until it reaches a point opposite the side blocks 13. The pins 12 then run off the upper end of the rails 62 and return to the position shown. While 55 however the feeding forward of the stamp is taking place the damping of the stamp will have been effected in the following manner: The plunger 1 carries a rack 22 and as this rack 22 descends with the plunger it 60 engages the pinion or ratchet wheel 23 and this pinion 23 is thus caused to rotate. In contact with the teeth of the pinion or ratchet 23 one end 24 of a lever 25 is arranged after the fashion of a pawl. The 65 lever 25 is pivoted at 26 and its end 27 de-

pends into the tank 28. The pivot 26 is preferably of some length and well fitted so as to prevent any leakage even if the machine is inverted. The extremity of the depending end 27 of this lever 25 is connected to a sliding plunger carrier 29 and this plunger carrier 29 has at its free end a rubber or other yielding plunger 30, the plunger 30 normally closing the jets or nozzles 31 arranged in the bottom of the tank. The 70 nozzles 31 are so located and bored in such a direction that the moisture ejected through them is sprayed on to the under adhesive surface of the stamp which is being fed forward through the slot 19. The movement 75 of the ratchet 23 causes a vibration of the lever 25 and thus the plungers 30 are intermittently oscillated and water flows from time to time to the nozzles or jets 31 as the plunger 30 withdraws and the water in 80 front of this plunger 30 is then ejected through the nozzles or jets as the plunger flies out again. It will be readily understood that at each depression of the machine 85 plunger 1 a number of separate ejections 90 of moisture is taking place in the same direction, the ejections starting when the stamp commences to protrude through the slot 19 into position to receive the moisture. It thus follows that the moisture will be 95 sprayed in definite jets and as the stamp travels to its final position the moisture will be applied to the adhesive surface of the stamp in an even and definite manner. The damped stamp is then cut off by the knife 100 100 21 as it passes the slot 19 and simultaneously the stamp will be pressed on to the envelop or other desired surface arranged beneath it. The pad 32 which presses the stamp on to the envelop or the like is as aforesaid of 105 special construction and operates in a particular manner. This pad is pivoted at 33 to the lower end of the plunger 1 and by means of the spring 34 or some other suitable yielding device it normally adopts an 110 angle to the horizontal as shown. The effect of this is that almost simultaneously with the severing of the stamp by the knife 21 the edge 35 of the pad contacts with the side of the stamp remote from the severed edge. 115 The continued descent of the plunger 1 causes the pad to gradually come into the horizontal position and thus the stamp is affixed by a horizontal movement and a vertical pressure, and it will be readily apparent that this is the movement required to cause a firm adhesion of the damped stamp upon the surface. Moreover this particular movement of the pressing pad has the advantage that the air between the stamp and the surface to which it is to be applied is expelled gradually as the pad approaches the horizontal and thus there is no danger of an air bubble becoming imprisoned beneath the stamp. Of course upon releasing the plun- 120 125 130

ger the whole of the working parts return to the normal position ready for the next operation and it should perhaps be mentioned that the construction shown of the 5 ratchet and lever operating the damping device is such that on the return movement no ejection of moisture takes place.

In order to prevent any possibility of drawing the strip out through the slot 19 a mutilating device is provided. This device 10 consists of an arm or arms 37 having harpoon or fish hook ends 38 and this arm projects toward the stamp strip but normally there is no contact between it and the stamp strip. In the ordinary legitimate operation 15 of the machine the strip can proceed around the curved lower end of the stamp strip guide 8 without contacting in any way with the mutilation arm 37 but if any attempt is 20 made to pull the strip through the slot 19 the strip immediately tends to straighten out and immediately this occurs the hinged members 39 upon the guide 8 move about the hinges 40 and the stamp strip becomes 25 impaled upon the harpoon end 38 of the arm 37 and thus mutilation of the stamp must take place and the machine is thus—for the moment—put out of action.

In order to prevent the forward edge of 30 the stamp strip catching as might occur if the stamp curled, I provide a clearing arm 41 which is connected to a pinion 42. A rack 43 gears with this pinion and the rack is carried upon a member or plate such as 35 44 provided with a cam slot 45 in which a pin 46 associated with the machine plunger operates. The operation is so timed that as the stamp moves into position the pinion 42 rotates on account of the rack 43 being 40 moved by the operation of the pin 46 in the cam slot 45. The arm 41 connected with the pinion 42 sweeps beneath the stamp and results in the front edge of the stamp being 45 cleared and moreover the arm serves to evenly distribute the previously supplied moisture over the surface of the stamp.

It will be understood that the casing of 50 the machine is constructed with a movable part or movable parts adapted to be locked in position so as to permit of easy access to the interior for purposes of examination and for renewal of the stamp spools so long as the proper keys are available. Of course 55 the details of construction of the machine can be varied in many ways without departure from the spirit and scope of my invention.

What I claim as my invention and desire 60 to secure by Letters Patent, is:—

1. In stamp delivery and affixing machines, a stamp affixing plunger, a strip gripping device carried by said plunger and normally free of the stamp strip, a regulating device having pins normally engaging perforations 65 of the stamp strip, means automatically op-

erating upon the descent of the stamp affixing plunger to cause the regulating device to free itself from the stamp strip and the gripping device to grip the stamp strip and feed it forward the required distance, means 70 for causing the feed regulating device to again engage the perforations in the stamp strip when a stamp has been fed forward, a device for moistening the strip, a device for severing the stamp, and an affixing device 75 actuated by said plunger, substantially as specified.

2. In stamp delivery and affixing machines, a stamp affixing plunger, a strip gripping device carried by said plunger and 80 normally free of the stamp strip, a regulating device having pins normally engaging perforations of the stamp strip, means automatically operating upon the descent of the plunger to cause the regulating device to 85 free itself from the stamp strip and the gripping device to grip the stamp strip and feed it forward the required distance, means for causing the feed regulating device to again engage the perforations in the stamp strip 90 when a stamp has been fed forward, means operated by the stamp affixing plunger for causing the ejection of moisture on to the under adhesive surface of the stamp, a severing device operated by said plunger, and an 95 affixing device operated by said plunger, substantially as specified.

3. In stamp delivery and affixing machines, a stamp affixing plunger, a strip gripping device carried by said plunger and normally free of the stamp strip, a regulating device having pins normally engaging perforations of the stamp strip, means automatically operating upon the descent of the plunger to cause the regulating device to 100 free itself from the stamp strip and the gripping device to grip the stamp strip and feed it forward the required distance, means for causing the feed regulating device to again engage the perforations in the stamp strip 105 when a stamp has been fed forward, means operated by the stamp affixing plunger for causing the ejection of moisture on to the under adhesive surface of the stamp, a serving device, and an affixing 110 device, substantially as specified.

4. In stamp delivery and affixing machines, a stamp affixing plunger, a strip gripping device carried by said plunger and normally free of the stamp strip, a regulating device having pins normally engaging perforations of the stamp strip, means automatically operating upon the descent of the plunger to cause the regulating device to 115 free itself from the stamp strip and the gripping device to grip the stamp strip and feed it forward the required distance, means for causing the feed regulating device to again engage the perforations in the stamp strip 120 when a stamp has been fed forward, means operated by the stamp affixing plunger for causing intermittent ejection of moisture on to the under adhesive surface of the stamp, a serving device, and an affixing 125 device, substantially as specified.

65 5. In stamp delivery and affixing machines, a stamp affixing plunger, a strip gripping device carried by said plunger and normally free of the stamp strip, a regulating device having pins normally engaging perforations of the stamp strip, means automatically operating upon the descent of the plunger to cause the regulating device to 130 free itself from the stamp strip and the gripping device to grip the stamp strip and feed it forward the required distance, means for causing the feed regulating device to again engage the perforations in the stamp strip when a stamp has been fed for-

ward, a damping device, a severing device, a pivoted stamp affixing pad actuated by the plunger, and a spring causing said pad to normally lie at an angle, substantially as 5 specified.

5. A stamp affixing machine, comprising a stamp affixing plunger, means operated by the stamp affixing plunger for feeding one stamp of the strip into the affixing position, 10 means for severing and affixing the stamp, and means operated by the stamp affixing plunger for causing the intermittent ejection of moisture onto the under adhesive surface of the moving stamp as it moves 15 into the affixing position and after it has passed through the severing device, substantially as specified.

6. In stamp delivery and affixing machines, a stamp affixing plunger, a strip gripping 20 device carried by said plunger and normally free of the stamp strip, a regulating device having pins normally engaging perforations of the stamp strip, means automatically operating upon the descent of the 25 plunger to cause the regulating device to free itself from the stamp strip and the gripping device to grip the stamp and feed it forward the required distance, means for causing the feed regulating device to again 30 engage the perforations in the stamp strip when a stamp has been fed forward, a mutilation device normally free of the stamp strip but adapted to pierce and mutilate 35 said stamp strip when tension is applied to the free end of the stamp strip, a damping device, a severing device, and an affixing device, substantially as specified.

7. A stamp delivery and affixing machine, comprising in combination, a stamp affixing 40 plunger, means for causing the intermittent ejection of moisture onto the adhesive surface of the stamp, a severing device, a strip tensioning device, and a regulating device adapted to feed the stamp strip forward the 45 required distance and into position for severing and affixing, and adapted to feed said stamp into position to protect the severing and affixing means from the moisture ejected onto the stamp.

50 8. A stamp delivery and affixing machine comprising in combination, a stamp affixing

plunger, a strip tensioning device carried by said plunger and normally free of the stamp strip, a regulating device having pins normally engaging perforations in the stamp strip, means automatically operating upon the descent of the plunger to cause the regulating device to free itself from the stamp strip, a gripping device to grip the stamp and feed it forward the required distance, 55 means for causing the feed regulating device to again engage the perforations in the stamp strip after a stamp has been fed forward, a mutilation device normally free of the stamp strip but adapted to pierce and mutilate 60 said stamp when tension is applied to the free end of the stamp strip, means for damping the stamp after it has left the working mechanism of the machine, and means for feeding the stamp into a position 65 whereby the working parts of the machine are protected from the moisture of the damping device, operated by the said affixing plunger.

9. In a stamp delivering and affixing machine, a stamp affixing plunger, a strip gripping device carried by said plunger and normally free of the stamp strip, a regulating device having pins normally engaging 70 perforations of the stamp strip, means automatically operating upon the descent of the stamp affixing plunger to cause the said regulating device to free itself from the stamp strip and the gripping device to grip the stamp strip and feed it forward the required distance, means for causing the feed regulating device to again engage the 75 perforations in the stamp strip when a stamp has been fed forward, a device for severing the stamp, means operated by the said stamp affixing plunger for causing the ejection of moisture after said stamp has passed through the severing device and as it moves 80 into the affixing position, and an affixing device actuated by said plunger, substantially 85 as specified.

In testimony whereof I affix my signature in presence of two witnesses.

CHARLES ASHTON HENRY BULLOCK.
